CIGARETTE-MAKING MACHINE.

1,089,680.

Specification of Letters Patent. Patented Mar. 10, 1914.

Application filed March 30, 1912. Serial No. 687,533.

To all whom it may concern:

Be it known that we, ROBERT ALEXANDER SLOAN and JOHN EDWARD LLOYD BARNES, subjects of the King of Great Britain, and residing in Liverpool, in the county of Lancaster, England, have invented certain new and useful Improvements in or Applicable to Cigarette-Making Machines, of which the following is a specification.

10 The object of this invention is to regulate or to facilitate the regulation of cigarette making machinery of the continuous type so that the cigarettes produced shall conform as nearly as possible to the weight intended, 15 and in carrying it into practice we provide a device for continuously weighing a specific number, say 100, of the cigarettes as they issue from the machine. In the simplest arrangement, the weight continuously indicated in this manner may serve as a guide to the machine operator directing him when to speed-up or to speed-down the tobacco feeding mechanism by hand, accordingly as the weighing device shows that the cigarettes are coming out below or above the intended weight. We prefer however to make the apparatus quite automatic, by combining with the weighing device a relay device controlled by the latter and adapted to regulate appropriately the speed controlling gear of the tobacco feeding mechanism.

20 We prefer generally to arrange the device to weigh the cigarettes as they issue from the cigarette making machine. Assuming that the number to be continuously weighed is 100, their weight would be about $\frac{1}{4}$ lb., and as the regulation should be within a small percentage, the balance must be very sensitive and not liable to be interfered with 25 by the cigarette propelling mechanism.

We have illustrated methods of carrying our invention into practice in the accompanying drawings of which—

Figure 1 is a diagrammatic view intended 30 to explain the invention broadly; Figs. 2 to 6 show one form of the apparatus in fuller detail, Fig. 2 being a plan and Figs. 3, 4, 5 and 6 sectional elevations on the respective lines A, A, B, B, C, C, and D, D, of Fig. 2. 35 Figs. 7, 8 and 9 show a modified construction in which the cigarettes are propelled along the weigh-beam by a chain conveyer, Fig. 7 being a plan, and Figs. 8 and 9 being sectional elevations on the respective lines 40 E, E, and F, F, of Fig. 7. The remaining figures are fragmentary detail views; Fig.

10 is a diagram showing the preferred scheme of electrical connections, Fig. 11 shows a mercurial contact device, and Figs. 12 and 13 show alternative mechanisms for operating the tobacco feed regulating spindle. Fig. 14 shows a device for indicating quantitatively the deviation in weight of the cigarettes above or below the normal.

Referring in the first instance to Fig. 1, which as already stated is merely diagrammatic, 1 is a weigh-beam fulcrumed on the knife edges 2 and carrying the pulleys 3 over which the endless traveling band 4 is strained. One of the pulleys 3 is positively geared to the cigarette making machine (without disturbing the poise as subsequently described) so that the speed of the band 4 is always proportional to that of the cigarette making machine, or in other words to the rate at which the cigarettes C are delivered by the cigarette making machine chute 5. 6 is a deflector which determines where the cigarettes land on the belt and they fall off at the other end on to a collecting belt 7 from which they are lifted off by the attendant. The band will obviously carry a constant number of cigarettes, this number being determined by the length occupied thereon by the cigarettes and the lineal speed of the band in relation to the speed of the cigarette making machine. 8 is a balance weight which keeps the weigh-beam horizontal when the weight of the cigarettes on the band is normal; if the cigarettes should come out lighter than intended the left end of the weigh-beam will rise and if heavier it will fall. In this way a specific number of cigarettes are continuously weighed in transit and in the absence of any automatic control the apparatus would serve as an indicator directing the machine operator when to speed-up or speed-down the tobacco feeding mechanism accordingly as the cigarettes are shown to be coming out below or above the intended weight. As stated, however, the regulation is preferably effected automatically by means of some form of relay and a typical form thereof of the electrical type is indicated. 9 is the tobacco feed regulating spindle of the cigarette making machine, upon which the ratchet wheel 10 is keyed, and this is adapted to be stepped around in either direction by the pawls L¹ and H¹ carried on the levers 11 which are linked as shown to the cores of the solenoids L² and H². One

pole of the battery 12 is coupled by the wire M^x to the elastic conducting prongs L^s , H^s , between which plays the stem 13 on the end of the weigh-beam. The other pole of the 5 battery is connected by the wire 14 to both solenoids where it divides, one branch L^s going around the solenoid L^2 to the fixed contact L^4 , and the other branch H^s going around the solenoid H^2 to the other fixed 10 contact H^4 . It will now be seen that if the cigarettes C should be coming out heavier than intended, the stem 13 will descend and close the electrical circuit of the solenoid H^2 , and this will operate the pawl H^1 and 15 the wheel 10 so as to reduce the speed of the tobacco feeding mechanism. In the actual construction, as subsequently described, the circuit is immediately afterward broken mechanically; and the step-by-step motion of 20 the wheel 10 is continued so long as the stem 13 remains down. As the correction takes effect, equilibrium is re-established, and the stem 13 gradually rises, and so long as it 25 remains clear of the prongs L^s , H^s , (that is to say, so long as the cigarettes come out at normal weight), the regulating spindle 9 remains in the position to which it was last adjusted. The action is of course similar, but in the reverse direction, so long as the 30 cigarettes are coming out below the normal weight, when the solenoid L^2 comes into action.

The construction shown in Figs. 2 to 6, which corresponds in its essential features with Fig. 1, will now be readily understood, 35 corresponding parts being indicated by corresponding reference numerals or letters as far as possible. The weigh-beam 1 is made of four angles 15 united by top and bottom and side bracing,—preferably of aluminium, 40 so as to form as light and rigid a structure as possible. The traveling band 4 is preferably made of two thicknesses of fabric with the transverse hardened steel wires 16 stitched between them at regular intervals; 45 these project at each side beyond the band and their ends are guided by the angles 15 and gear with sprockets on the pulleys 3. By this arrangement the band need not be 50 tightly strained, as the drive is positive, and the wires being guided, they keep the band flat and prevent it from sagging. Very little force is thus required to drive the band. The knife edges 2 are carried by the cross angles 17 fixed across the top of the weigh- 55 beam, and rest upon the bolsters 18 carried on the cross bar 19 fixed to the main frame 20. 21 is the end of the cigarette making machine and 22 one of its spindles,—preferably the one operating the cut-off mechanism. The drive is transmitted therefrom by the screw gear wheels 23 and chain gear 24 to the shaft 25 which is arranged with its axis exactly on the level of the knife edge line and at right angles thereto. 26 is a 60 light shaft in line with the shaft 25, mount-

ed in the bearings 27 on the plate 28 integral with the weigh-beam. This drives through the worm gear 29, spindle 30 and chain gear 31, the pulley 3 of the band 4. The drive is transmitted from the shaft 25 70 to the shaft 26 through the short shaft 32 and the Hooke's couplings 33, 33', the latter coupling having its swivel lines intersecting exactly on the knife-edge line. So arranged, the drive cannot transmit any turning effort which can disturb the poise of the weigh-beam. The balance weight 8 has one portion 8^a adjustable vertically and one portion 8^b adjustable horizontally, so that the stability can be adjusted and the weigh-beam brought exactly into poise when unloaded. 34 is a stud with a wing nut by means of which the weights 35, which determine the weight of the cigarettes produced, are detachably secured to the weigh-beam. 36^a 36^b is a dash pot arrangement to damp accidental vibrations; being clearly shown in Fig. 3, it is omitted for the sake of clearness from Fig. 5. It consists of a can 36^a 85 fixed to the weigh-beam, with leakage holes 36^c in its bottom, partially immersed in glycerin held in the outer vessel 36^b which is carried from the main frame 20. This offers no static resistance but has a very effective damping effect, and the latter can be adjusted within considerable limits by means of a rotary hit-and-miss plate (not shown), fitted on the bottom of the can 36^a. The relay here shown is of the electrical type, controlling a solenoid operating mechanism as 100 described with reference to Fig. 1 and shown in fuller detail in Fig. 12.

The variation in weight permissible is very small, and any electrical contact devices operated by the weigh-beam should be 105 of a delicate character not adapted to directly close or break a circuit carrying a current sufficiently strong to operate the solenoids L^2 , H^2 . We accordingly use the arrangement shown diagrammatically in 110 Fig. 10.

37, L^5 , H^5 is a contact piece or commutator carried by the free end of the weigh-beam. The central part 37 is of glass or the like, and the parts L^5 , H^5 , are of metal. The 115 three parts are insulated from each other and from the weigh-beam. The three elastic prongs M , L and H form the terminations of the wires lettered M^x , L^x and H^x in Fig. 1, and they are carried on the insulating arm 120 38 fixed to the spring-controlled reciprocating rod 39. The three prongs stand normally clear of the contact pieces 37, L^5 , H^5 but they are periodically moved up into contact by the mechanism shown most clearly 125 in Fig. 4.

40 is a worm on the shaft 25 driving a worm wheel 41 carrying a projecting pin 42 which at each revolution trips the trip lever 43 connected to the rod 39 by the wire 44. 130

45 is a metal cylinder mounted by an insulating core on the shaft 46 of the worm wheel 41; it is shown of two diameters in Fig. 10 but this is merely for the sake of greater clearness. Four prongs or brushes make contact with this cylinder. Of these, M¹ bears continuously on the cylinder, L⁶ and H⁶ stand normally clear of it but are drawn down into contact with it when their respective small solenoids L⁷ and H⁷ are energized; the greater part of the cylinder is cut away in the line of the fourth brush 47, so that only a segment 45^a remains. The electrical connections are clearly shown in Fig. 10.

When the weigh-beam is in neutral position as shown in Fig. 10, or only very slightly out of balance, the prong M can only make contact with the glass part 37, and none of the circuits are then closed. If the free end of the weigh-beam descends farther, then both prongs M and H come into contact with the conducting part H⁶ when the rod 39 is advanced. Immediately afterward, the brush 47 makes contact with the segment 45^a and the circuit is completed from the battery 12 through wire 49, brush 47, cylinder 45, brush M¹, wire M⁸, part H⁵, wire H⁸, around small solenoid H⁷, around large solenoid H², and back to battery by wire 14. The solenoid H⁷ being energized, it pulls the brush H⁶ into contact with the cylinder 45, giving much better contact than is afforded by the prongs M and H and the part H⁶, so that the main current passes from the battery by the wire 49, brush 47, segment 45^a, brush H⁶, around small solenoid H⁷, around large solenoid H², (which then makes its working stroke), and back to battery by wire 14. Before the prongs retreat from the part H⁶, the segment 45^a leaves the brush 47 and so breaks the circuit of both the small and the large solenoids. It will be seen that by this arrangement there can be no sparking at the prongs M, L and H, as the current is neither made nor broken by them, and they only require to carry a current heavy enough to energize the smaller solenoids. The action is of course similar when the free end of the weigh-beam rises so as to bring the part L⁵ into line with the two prongs M and L; in these circumstances the solenoid L² operates the wheel 10 in the reverse direction each time the prongs M, L and H make their forward stroke.

The device shown in Fig. 12 for operating the tobacco feed-regulating spindle 9 has been described in connection with Fig. 1, and it is only further necessary to explain how the stroke is regulated and the pawls kept clear of the wheel teeth when not in action. 48 are adjustable stops carried by the base of the frame and abutting below the levers 11, so that the number of teeth taken at each stroke can be regulated. 49

are radial stems on the pawls, and 50 are adjustable stops carried by the frame base. Just before the levers 11 reach the bottom of the stroke, these stems 49 abut against the stops 50 and tilt the pawls back clear 70 of the wheel teeth until the pawls begin to lift again. Instead of the device last described, the alternative form shown in Fig. 13 may be used. The wheel 10 is now made as a worm wheel, driven by the worm 51 fixed on the shaft 52. 53 are a pair of miter wheels riding loosely on the shaft 52 and driven in opposite directions by the central miter wheel 54 which latter rotates continuously. 55 are magnetic clutches by 80 which either of the miter wheels 53 can be clutched to the shaft. The electric leads L and H from the weigh-beam contact device and 14 from the battery are coupled to the clutches as shown by rubbing contacts 85 of the usual type, and it will be seen that when the current flows through 14 and L⁸ the tobacco feed-regulating spindle 9 will be turned in one direction, and will be turned in the reverse direction when the current flows through 14 and H⁸. While no current flows, the spindle 9 remains at rest.

The contacts controlled by the weigh-beam might be in the form of wires dipping into mercury, but owing to the well-known objections to the use of such contacts for prolonged service, we prefer to use the form already described in ordinary cases. If a mercurial contact is to be used, we prefer the form shown in Fig. 11, where 56 is a 100 curved glass tube mounted on the weigh-beam and partially filled with mercury 57. The tube is sealed under vacuum and the three terminals M⁹, L⁹ and N are fused through the glass. The tilting of the tube 105 in either direction will obviously establish the electric circuits in the required manner.

As it is desirable that the weigh-beam should not merely indicate the fact that the cigarettes are coming out heavier or lighter than normal, but should also give a quantitative indication of the amount of the excess or deficiency in weight, we fit the device shown in Fig. 14. This consists of a 110 light pointer 58 delicately pivoted at 59 on the weigh-beam near its free end. This pointer has a depending arm 60 with a balance weight 61,—(or it might be controlled by a light spring),—and it has a stem 62 115 playing between fixed banking pins 63. These pins are far enough apart to allow the weigh-beam to swing either up or down far enough to operate the relay before the pins abut against the stem 62, so that the present device in no way affects the sensitiveness of the automatic control action. Any further excess or deficiency of the weight will then be indicated by the pointer against the fixed scale 64 which may read percentages. 120 125 130

The pointer might obviously be balanced on a fixed pivot, and the banking pins be fixed to the weighbeam, but the arrangement shown has the advantage that only a single pointer and scale are required.

In the modification shown in Figs. 7, 8 and 9, the cigarettes are rolled along the weigh-beam, resting on the angles 15 thereof, and being propelled by the vanes 65 fixed 10 to the endless pitch chain 66 running over the sprocket wheels 67 carried in the brackets 68 fixed to the frame of the machine. As before, the pitch chain is driven by a positive gear from the cigarette making machine, so that one space between the vanes is 15 presented for each cigarette as it is delivered by the cigarette making machine. The vanes being vertical do not support any part of the weight of the cigarettes which falls 20 entirely on the track formed by the weigh-beam. The cigarettes may be caught as they issue from the chute 5 (shown at the right hand position, Fig. 8) into the spaces between the vanes rolling for a short distance 25 along the fixed track 69 at the end of which they fall on to the weigh-beam track. At the right hand end of the latter they fall on to a second fixed track 70 from which they might fall on to a collecting belt but to 30 economize length we show this fixed track 70 curved around so as to return the cigarettes to the lower pair of angles 15 along which they make a return journey finally falling off at the left end of the weigh-beam 35 track on to the collecting belt which is not shown. The vanes are of course evenly pitched and the weigh-beam track is of the exact length to hold, say 100 cigarettes one rolling off at the delivery end as one rolls 40 on at the receiving end. We have found however that, owing to slight irregularities in the delivery of the cigarettes from the cigarette making machine, a cigarette may occasionally fail to enter fairly into the corresponding 45 space between the conveyer vanes, and, owing to the very rapid rate of delivery, such an occurrence is apt to disarrange several of the following cigarettes and so interfere with the continuous and accurate working of the apparatus. To meet 50 this difficulty, we prefer to receive the cigarettes from the cigarette making machine chute 5 on a traveling endless band 71, and to transfer them therefrom into the spaces 55 between the conveyer vanes. The cigarettes pass off the band 71 over a fixed bridge plate 72 which is curved downwardly and has its lower edge 73 turned upwardly. The cigarettes are crowded together slightly 60 as they encounter the fixed edge of the plate, and if any are lying not quite squarely across the band, they are set square and pushed along until they roll down the slope being stopped by the upturned lower edge 65 73. The lower end of the slope has a gap

74 through which the ends of the conveyer vanes 65 sweep in succession with just enough reach to carry away the lowermost cigarette. There is always a store of a few cigarettes resting on the slope, and any slight irregularity in the delivery is thus compensated for. To insure that the cigarettes shall be in alinement endwise, we provide a pair of small round or square endless traveling belts 75 lying close above the collecting band and converging toward the delivery end, where they are separated by rather more than the length of a cigarette. The resolved speed of these belts conforms with that of the cigarettes and the latter are thus gradually pushed into alinement as they travel. This device may also be useful for moving the cigarettes endwise across the collecting belt on which they ultimately fall, so as to bring them into a more convenient position for removal by the attendant.

Having now fully described our invention, we declare that what we claim, and desire to secure by Letters Patent is;—

1. In combination with a cigarette machine, a weighing device comprising an adjustable weight and a movable part over which the cigarettes pass in a continuous stream and at a rate proportional to the speed of the machine, said movable part and adjustable weight being normally balanced over a common fulcrum in such manner that the number of cigarettes supported by the said weighing device is always the same, and means for indicating continuously the position of the said movable part in respect to its balanced or zero position, substantially as described.

2. In combination with a cigarette machine;—a weighing device comprising an adjustable weight and a movable part over which the cigarettes pass in a continuous stream and at a rate proportional to the speed of the machine, and an organization controlled by the movement of the said movable part and adapted to actuate a part the movement of which regulates the rate of feed of tobacco to the cigarette machine; substantially as described.

3. In combination with a cigarette machine; a weighing device comprising a weigh-beam and a traveling endless belt to receive and transmit the cigarettes and means for driving the said belt at a rate in synchronism with that of the cigarette machine in such manner that the number of cigarettes supported by said weighing device is always the same; substantially as described.

4. In combination with a cigarette machine;—a weighing device comprising a weigh-beam and conveyer belt and driving device therefor carried by the said scale beam, a part rotated in synchronism with

the cigarette machine, and means for transmitting a torque to the weigh-beam tending only to rotate the latter about an axis perpendicular to the axis of the knife edges thereof, and adapted to transmit the movement of the said rotated part to the said driving device; substantially as described.

5. In combination with a cigarette machine;—a weighing device comprising a weigh-beam and conveyer belt adapted always to support a constant number of cigarettes and driving device therefor carried by the said scale beam, a part rotated in synchronism with the cigarette machine, and a shaft located at right-angles to the scale-beam knife edge axis, and adapted to connect the said rotated part to the said driving device; substantially as described.

6. In combination with a cigarette machine;—a weighing device comprising a weigh-beam and conveyer belt and driving device therefor carried by the said scale beam, a part rotated in synchronism with the cigarette machine, and a universal coupling having pivots the axis of which coincides with the axis of the scale-beam knife edges; substantially as described.

7. In combination with a cigarette machine;—a weighing device comprising a weigh-beam and a traveling endless belt to receive and transmit the cigarettes, means for driving the said belt at a rate in synchronism with that of the cigarette machine, and an organization controlled by the movement of the said scale-beam and adapted to actuate a part the movement of which regulates the rate of feed of tobacco to the cigarette machine; substantially as described.

8. In combination with a cigarette machine;—a weighing device comprising a weigh-beam and conveyer belt and driving device therefor carried by the said scale beam, a part rotated in synchronism with the cigarette machine, means for transmitting a torque to the weigh-beam tending only to rotate the latter about an axis perpendicular to the axis of the knife edges thereof, and adapted to transmit the movement of the said rotated part to the said driving device; and an organization controlled by the movement of the said scale-beam and adapted to actuate a part the movement of which regulates the rate of feed of tobacco to the cigarette machine; substantially as described.

9. In combination with a cigarette machine;—a weighing device comprising a weigh-beam and conveyer belt and driving device therefor carried by the said scale beam, a part rotated in synchronism with the cigarette machine, a shaft located at right-angles to the scale-beam knife edge axis, and adapted to connect the said rotated part to the said driving device; and an organization controlled by the move-

ment of the said scale-beam and adapted to actuate a part the movement of which regulates the rate of feed of tobacco to the cigarette machine; substantially as described.

10. In combination with a cigarette machine;—a weighing device comprising a weigh-beam and conveyer belt and driving device therefor carried by the said scale beam, a part rotated in synchronism with the cigarette machine, a universal coupling having pivots the axis of which coincides with the axis of the scale-beam knife edges, and an organization controlled by the movement of the said scale-beam and adapted to actuate a part the movement of which regulates the rate of feed of tobacco to the cigarette machine; substantially as described.

11. In combination with a cigarette machine;—a weighing device over the movable part of which the cigarettes pass, a source of power which can be directed to operate in either direction the device which regulates the feed of the cigarette machine, and means actuated by the weighing device and adapted to direct the said source of power so that the feed regulating device is operated in the one direction or in the opposite direction, accordingly as the weighing device is over-poised or under-poised, substantially as described.

12. In combination with a cigarette machine;—a weighing device over the movable part of which the cigarettes pass, electro-magnetic means for controlling in either direction the movement of the part which regulates the feed of the cigarette machine, a source of electrical energy and electrical contacts some of which are on the movable part of the weighing device, connected to the said electro-magnetic means and source and adapted when the weighing device is over-poised to connect the electro-magnetic means to the source so as to cause the movement of the feed regulating part in the one direction, and when the said device is under-poised to connect the electro-magnetic means to the source so as to cause the movement of the said part in the opposite direction; substantially as described.

13. In combination with a cigarette machine;—a weighing device over the movable part of which the cigarettes pass, electro-magnetic means for controlling in either direction the movement of the part which regulates the feed of the cigarette machine, a source of electrical energy and electrical contacts some of which are on the movable part of the weighing device, connected to the said electro-magnetic means and source, said contacts being adapted when closed to connect the respective circuits of the electro-magnetic means to the source; means moving synchronously with the cigarette machine adapted to close said contacts, and a circuit breaking device actuated synchronously with

- the cigarette machine and adapted to open the said circuits; substantially as described.
14. In combination with a cigarette machine;—a weighing device over the movable part of which the cigarettes pass, electro-magnetic means for controlling in either direction the movement of the part which regulates the feed of the cigarette machine, a source of electrical energy and electrical contacts some of which are on the movable part of the weighing device, connected to the said electro-magnetic means and source and adapted when closed to operate one or other of two relay circuits according as the movable part of the weighing device is under-poised or over-poised, said relays closing the respective circuits of the electro-magnetic means; and means for independently opening the latter circuits; substantially as described.
15. In combination with a cigarette machine;—a weighing device comprising an adjustable weight and a movable part over which the cigarettes pass in a continuous stream and at a rate proportional to the speed of the machine, and pivoted indicating means articulated to said movable part and having a gravity piece which is in its lowest position when the weighing device is in poise; substantially as described.
16. In a cigarette machine in combination;—a weigh beam, a conveyer band carried thereby and driven synchronously with the cigarette machine, an electro-magnetic device to move the feed screw of the cigarette machine so as to accelerate the feed, an electro-magnetic device to move the said feed screw in the opposite direction, a source of electrical energy, contacts on the weigh-beam, means moving synchronously with the cigarette machine and adapted to close said contacts so that the said source may be connected to the one electro-magnet when the weigh-beam is over-poised, and to the other when it is under-poised; substantially as described.
17. In a cigarette machine in combination;—a weigh beam, a conveyer band carried thereby and driven synchronously with the cigarette machine, an electro-magnetic device to move the feed screw of the cigarette machine so as to accelerate the feed, an electro-magnetic device to move the said feed screw in the opposite direction, a source of electrical energy, contacts on the weigh-beam, means moving synchronously with the cigarette machine and adapted to close said contacts so that the said source may be connected to the one electro-magnet when the weigh-beam is over-poised, and to the other when it is under-poised; and a switch moving synchronously with the cigarette machine and adapted to open the circuits connected by the contacts before said contacts are opened; substantially as described.
18. In a cigarette machine in combination;—a weigh beam, a conveyer band carried thereby and driven synchronously with the cigarette machine, an electro-magnetic device to move the feed screw of the cigarette machine so as to accelerate the feed, an electro-magnetic device to move the said feed screw in the opposite direction, a source of electrical energy, contacts on the weigh-beam, means moving synchronously with the cigarette machine and adapted to close said contacts so that the said source may be connected to the one electro-magnet when the weigh-beam is over-poised, and to the other when it is under-poised; and a switch moving synchronously with the cigarette machine and adapted to close the circuits connected by the contacts after said contacts are closed and to open said circuits before said contacts are opened; substantially as described.

In testimony whereof, we affix our signatures in presence of two witnesses.
